(57) **CLAIM**

The ornamental design for generator, as shown and described.

DESCRIPTION

FIG. 1 is a perspective view of a generator showing my new design;

FIG. 2 is a top plan view thereof;

FIG. 3 is second perspective view thereof, shown in a separated condition; and,

FIG. 4 is a right-side elevation view thereof, shown in separated condition.

The "AKWA" trademark forming part of the claimed design is a trademark registered in Germany belonging to Mikhail Seropjan.
